UNITED STATES PATENT OFFICE

ROBERT E. FRUIN, OF CHICAGO, ILLINOIS

HORSESHOE

Application filed December 29, 1930. Serial No. 505,228.

This invention relates to a type of horseshoe commonly known as "semi-cushion tread" shoes. This type of shoe is characterized by a metal frame, a thick rubber heel 5 cushion at the rear end only of the frame, and one or more sharp toe calks at the front end of the frame; the object being to provide a shoe adapted for service on both dry and slippery pavements or roadways, giving the 10 animal a cushioned tread and a good grip on a dry pavement and also a secure hold on a wet or ice-covered pavement.

As above stated, my present improvement relates to shoes of the above type; and among 15 the objects of the invention are, to provide a stronger and more durable shoe than has heretofore been known, to provide in a shoe of this type greater security against slipping in all directions and particularly against 20 side slip and twisting on slippery pavements which are liable to produce severe sprains of the animal's leg, to provide a shoe having a frame of mild malleable steel which can be forged cold to fit hoofs of slightly varying 25 widths and at the same time is reinforced to prevent accidental downward bending of the toe portion when in service, to provide a shoe of simple and inexpensive construction combining a full length one-piece frame with 30 single heel pad or cushion, side calks at the quarter, and an open center affording full ventilation to the frog, to provide a shoe having straight-edge side and toe calks so mounted on the frame as to require no fastening or securing devices and be readily removed and replaced by new calks and also angularly adjustable to present their straight edges at any desired angle to the direction of 35 travel, and, generally, to provide a simpler, better and more efficient shoe for all weather conditions than the art has thus far produced.

Still other objects and attendant advantages of the invention will be apparent to 45 horseshoers and others skilled in the art from the following detailed description, taken in connection with the accompanying drawings wherein I have illustrated a desirable physical form or embodiment of the invention well

adapted to effectuate the stated purposes and objects thereof, and in which—

Fig. 1 is a bottom plan view of the metal frame;

Fig. 2 is a bottom plan view of the complete shoe;

Figs. 3, 4, and 5 are detail cross-sectional views taken on the lines 3—3, 4—4 and 5—5, respectively, of Fig. 2; and

Fig. 6 is a median longitudinal section 60 through the complete shoe, taken on the line 6—6 of Fig. 2.

Referring to the drawings, the frame of the shoe, best shown in Fig. 1 and designated as an entirety by 10, is a metal forging, preferably of mild malleable steel, having the usual horseshoe outline form, and provided in its sides with the usual rows of nail-holes 11. In the forging operation the metal is so distributed as to form on the bottom of the frame 65 a pair of depending bosses 12 located forwardly of the nail-holes 11; a pair of depending bosses 13 located in rear of said nail-holes, a pair of pad seats or sockets 14 located in rear of the bosses 13, and a pair 70 of depending stiffening ribs 15 extending between and merging into the bosses 12 and 13, and lying inwardly of the nail holes 11 and bordering the inner edges of the sides of the frame.

Anchored in the seats 14 and spanning the rear ends of the sides of the frame is a thick solid rubber pad or cushion designated as an entirety by 16. The bottom walls of the seats 14 are formed with holes or slots 17 by which 75 the pad, when vulcanized, is keyed to the frame, as clearly shown in Fig. 5. No novelty for this pad and its mounting is claimed herein, as the same is practically identical with that disclosed in my former patent on a cushion-tread horseshoe No. 1,690,365, dated November 6, 1928.

The bosses 12 and 13 are formed with round 80 slightly tapered holes 18 and 19, respectively, into which are driven for a tight fit the round tapered shanks or stems 20 and 21 respectively of a pair of toe calks 22 and side calks 23. These calks are preferably of the straight-edge type taking the forms clearly shown in 85 Figs. 4 and 6, and presenting straight com-

paratively sharp cutting edges to the surface of the road or pavement.

By reference to Fig. 2 it will be seen that the side calks 23 are located well rearwardly on the sides of the shoe frame, behind the rearmost of the nailing holes and just in advance of the ends of the pad. This location of the side calks, which I believe to be novel with my present invention, is very advantageous in the way of preventing both side slip and twisting of the hoof on the pavement. Side calks, in addition to toe calks, have hitherto been known broadly, but so far as I am aware the side calks have been located so far forwardly on the sides of the frame as to be of little aid to the toe calks in preventing side slip or twisting. By reference to Fig. 6 it will be seen that the lower ends of the side calks 23 are substantially flush with the bottom of cushion pad 16, so that the pad and the side calks engage with the road or pavement throughout the rear half of the shoe.

The described structure of calks and mounting means therefor enables the calks, when unduly worn, to be driven out and readily replaced by new calks, which is a pronounced economy over shoes formed with integral calks; and it also permits the tread edges of the calks to be set at any desired angle. The two toe calks 22 are preferably so mounted that their tread edges will extend substantially at right angles to the longitudinal median line of the shoe, which affords the best toe traction to the animal when drawing a heavy load or climbing a hill. The side calks 23 will preferably be set oblique, as shown by full lines in Fig. 2; but for heavy pulling they may advantageously be set in the same direction as the toe calks 22, as shown by dot and dash lines at the right in Fig. 2; while on icy pavements whereon the animal is liable to slip in any direction, the side calks 23 will preferably be set substantially parallel with the longitudinal median line of the shoe, as indicated by dotted lines at the left in Fig. 2, so that, while the toe calks prevent forward and rearward slip, the side calks will be equally effective to prevent side slip.

It has not infrequently been demonstrated, by actual experience, that the horse shod with a shoe having a plain flat frame equipped with toe calks will sometimes strike the toe calks so hard against an obstruction on the road as to bend the fore part of the frame downwardly and pull loose the foremost fastening nails in the hoof. I have also hereinabove referred to the frame as preferably being forged from mild or soft steel. The purpose of this is to enable the same size of shoe to be used on hoofs varying slightly in width. If the hoof is too narrow for a good fit, the sides of the shoe frame can be swaged inwardly, and vice versa, if the hoof is slightly too wide the sides can be swaged apart, both

operations being practical without heating the frame. It will be observed that the rubber pad 16 has a central forwardly bowed portion, which permits the slight narrowing or widening of the sides of the frame above referred to after the pad has been vulcanized in place. Now with a mild steel frame of this kind, the accidental bending above referred to is quite liable to occur; and with a view to preventing this, I have provided the reinforcing ribs 15 extending on each side between the calk bosses 12 and 13. With these reinforcing ribs, mild steel can be used in the manufacture of the frame without any danger of the accidental bending of the latter in service.

From the foregoing it will be seen that the invention provides a shoe well adapted for year-round service. The wide, thick heel pad 16 affords cushion tread for the rear or most tender part of the animal's foot, while the four calks afford security against slipping on wet and icy pavements without nullifying the cushioning effect of the heel pad. The structure is simple, comprising only six assembled parts, namely, the frame, the pad, and the four calks; and the economy is still further enhanced by the renewable character of the calks. While some of the individual structural features of my improved shoe, such as the heel pad and renewable calks, are broadly old and known in other constructions of shoes, I believe that the combinations pointed out in the appended claims, whereby the individual elements and structural features cooperate to produce a better and more efficient and durable horseshoe of the type described, are new and useful.

I claim:

1. In a horseshoe of the type described, the combination of a one-piece full length metal shoe frame formed with rows of nail-holes in its sides, a heel pad mounted on the under side of the rear end portion of said frame, a toe calk located on the front of the frame, and a pair of side calks respectively located on the sides of the frame between the rearmost nail-holes and the ends of said pad, the shoe having an open center for ventilating the frog of the hoof.

2. In a horseshoe of the type described, the combination of a one-piece full length metal shoe frame formed with rows of nail-holes in its sides and pad seats in rear of said rows, a single heel pad anchored at its ends in said seats and spanning the space between the latter, a removable toe calk mounted on the front of the frame, and a pair of removable side calks respectively mounted on the sides of the frame between the rearmost nail-holes and the ends of said pad, the shoe having an open center for ventilating the frog of the hoof.

3. In a horseshoe of the type described, the combination of a one-piece full length metal

shoe frame formed with rows of nail-holes in its sides, a pair of front calk holes located forwardly of said rows and a pair of side calk holes located in rear of said rows, a heel pad anchored to and spanning the rear ends of the sides of the frame in rear of said side calk holes, removable toe calks formed with shanks tightly fitting said front calk holes, and removable side calks tightly fitting said side calk holes.

4. In a horseshoe of the type described, the combination of a one-piece full length metal shoe frame formed with rows of nail-holes in its sides, a pair of round tapered calk holes located forwardly of said rows, and a pair of round tapered side calk holes located in rear of said rows, a heel pad anchored to and spanning the rear ends of the sides of the frame in rear of said last-named calk holes, straight-edge toe calks formed with round tapered shanks having a drive fit in said forward calk holes, and similar calks having a drive fit in said side calk holes, the tread edges of said last-named calks being substantially flush with the tread surface of said heel pad.

5. In a horseshoe of the type described, the combination of a one-piece full length metal horseshoe frame laterally expansile and contractile when cold and formed with rows of nail-holes in its sides, a pair of toe calks mounted in said frame forwardly of said rows, a pair of side calks mounted in said frame in rear of said rows, a centrally bowed heel pad anchored to and spanning the rear ends of the sides of the frame in rear of said side calks, and integral stiffening ribs on the under side of said frame extending between said front and side calks.

6. In a horseshoe of the type described, the combination of a one-piece full length metal horseshoe frame laterally expansile and contractile when cold and formed with rows of nail-holes in its sides, a pair of removable toe calks mounted in said frame forwardly of said rows, a pair of removable side calks mounted in said frame in rear of said rows, a centrally bowed heel pad anchored to and spanning the rear ends of the sides of the frame in rear of said side calks, and integral stiffening ribs on the under side of said frame extending between said front and side calks and disposed inwardly of said rows of nail-holes.

7. In a horseshoe of the type described, the combination of a one-piece full length metal horseshoe frame laterally expansile and contractile when cold and formed with rows of nail-holes in its sides, a pair of depending bosses located forwardly of said rows, and a pair of depending bosses located in rear of said rows, said bosses formed with holes to receive calks, a pair of straight-edge toe calks formed with shanks having a drive fit in the holes of said forward bosses, a similar pair of side calks having a drive fit in the holes of

said rear bosses, a centrally bowed heel pad anchored to and spanning the rear ends of the sides of the frame, and integral stiffening ribs on the under side of said frame in rear of said rear bosses, said ribs being located inwardly of said rows of nail-holes and at their ends merged into said forward and rear bosses.

CERTIFICATE OF CORRECTION.

Patent No. 1,889,856.

December 6, 1932.

ROBERT E. FRUIN.

It is hereby certified that error appears in the printed specification of the above numbered patent requiring correction as follows: Page 3, line 67, claim 7, for "an" read "and"; and lines 69 and 70, strike out the words "in rear of said rear bosses" and insert the same after "frame" in line 68; and that the said Letters Patent should be read with these corrections therein that the same may conform to the record of the case in the Patent Office.

Signed and sealed this 24th day of January, A. D. 1933.

(Seal)

M. J. Moore,
Acting Commissioner of Patents.
